KARL WOLLNY, OF WEISSENFELS-ON-THE-SAALE, GERMANY, ASSIGNOR TO THE FIRM NOLLESCHE WERKE KOMMANDIT GESELLSCHAFT, OF WEISSENFELS-ON-THE-SAALE, GERMANY

MACHINE FOR THE MANUFACTURE OF TEMPLATES

Application filed July 19, 1930, Serial No. 469,287, and in Germany December 11, 1929.

My invention relates to a machine for the manufacture of pattern plates or templets for cutting out and marking uppers or other shoe parts. These templets are well known in the art. They consist of a card-board body carrying small metallic plates provided with marking points. The plates are formed with integral tongs by which they are secured to the body. The templets are laid upon the leather or the fabric to be cut. The operator presses the templet with the left hand upon the goods and cuts the goods by guiding with the right hand the knife along the edge of the templet. By the same operation the said points are pressed into the goods and small recesses are produced therein which form marks serviceable when connecting the cut out parts with other shoe-parts.

Now the plates with the marking points are fastened on both sides of the templets for corresponding parts of left and right shoes. It is of extreme importance that the points lie on both sides in strict alinement. But this accuracy is not to be obtained by fastening the pointed plates by hand as it is generally done.

The primary object of my invention resides therefore in the provision of a machine adapted to fasten the pointed plates simultaneously on both sides of the templet.

An important feature of the invention lies in the arrangement of means adapted to hold and to fasten the said plates in alinement on the opposite sides of the templets.

These and other features of the invention will be more apparent from the following description and the annexed drawings.

Fig. 1 is a side elevation and Fig. 2 a front view of the machine, some parts being broken away for the sake of clearness; Fig. 3 is a section on the line *a*—*b* of Fig. 1; Fig. 4 shows a templet; Fig. 5 is a cross-section of the templet through the marking points; Fig. 6 is an enlarged sectional elevation of the hammer for fastening the plates; and Figs. 7, 8, and 9 illustrate in vertical sectional views the initial, middle, and end position of the hammers respectively.

The shaft 2 journaled in the frame 1 carries the lever 3 having a cam 4. The lever

3 can be pulled down by the treadle 5 and is again raised by the spring 6. To the lever 3 are pivoted at 7 and 7' the links 8, 8' connected by the two-armed levers 9, 9' to the pistons 10, 10' respectively, so that both pistons are moved against each other by the depression of the treadle. Within the pistons are guided the sleeves 11, 11' pressed outwardly by the springs 12, 12' respectively. Pins 14, 14' of the pistons project into slots 13, 13' of the sleeves and limit the outward movement of the sleeves. The sleeves form guides for the driving plungers 15, 15' held in the outer position by the springs 16, 16' attached at one end to the pins 31 fixed to the frame and at the other ends to the pins 32 fixed to the driving plungers. The pins 32 move in slots 33 of the frame and the ends 1' of the slots limit the outer position of the hammers. The heads 28' of the driving plungers are enclosed by sleeves 17, 17' for centrally positioning of the marking plates 26. These sleeves 17, 17' are allowed to retreat by the springs 18' when the driving plungers are fastening the plates 26 to the templets.

On the bolt 19 is fastened the swinging lever 20. Owing to the spring 22 the bolt 21 of the lever 20 remains in contact with the cam 4 of the lever 3. To the lever 20 is adjustably secured by a screw 23 a feeling finger 24. This finger is provided at its end with a point 25 adapted to enter into the holes 25' made in the templet body by a needle or the like for indicating the location of the pointed plates 26 on the templet.

The machine is operated as follows:

The pointed plates 26 are placed into the sleeves 17, 17' of the driving plungers as shown in Fig. 6. The heads 28' of the driving plungers are magnetic so that the pointed plates 26 adhere thereto. The templet body is now so introduced into the machine that the point 25 of the finger 24 enters into a hole 25' of the templet. In this position the point 25 is just in the axis of the hammers 15, 15'. By depressing the treadle 5 the pistons 10, 10' and the sleeves 11, 11' are moved against each other, while the hammers 15, 15' owing to the springs 16, 16' remain so

long in their outer position until they come into contact with the surfaces 29 of the pistons 10, 10' whereupon they move with the latter against the templet. The sleeves 11, 11' at first take hold of the templet 27, see Fig. 8. Then the feeler 24 retreats through the slot 30 of the sleeve 11' and the hammerheads 28' with the pointed plates 26 sit down upon the templet. Finally the prongs of the pointed plates 26 are forced into the body of the templet and the treadle is released. All parts are returned into their initial position by the springs provided therefor.

What I claim is:

In a machine for the manufacture of templets of the kind described, means for clamping the templet to be worked upon, means for positioning the templet prior to its clamping, and means for simultaneous fastening two separate marking members on both sides of the clamped templet consisting of two plungers moved at first yieldingly for clamping the templet and then moved positively for driving the marking members.

In testimony whereof I affix my signature.
KARL WOLLNY.
